CLAIM

The ornamental design for a tool handle, as shown and described.

DESCRIPTION

FIG. 1 is a top, front and left perspective view of the tool handle showing my new design;

FIG. 2 is a top plan view thereof;

FIG. 3 is a bottom plan view thereof;

FIG. 4 is a front elevational view thereof;

FIG. 5 is a right side elevational view thereof; the left side being a mirror image;

FIG. 6 is a rear elevational view thereof;

FIG. 7 is a cross-sectional view taken along lines 7—7 of FIG. 1;

FIG. 8 is a top, front and left perspective view of a second embodiment of my new design;

FIG. 9 is a front elevational view thereof; and,

FIG. 10 is a rear elevational view thereof.

The spatula in FIGS. 1 and 8 is shown in broken lines for illustrative purposes only and forms no part of the claimed design.
